[57] CLAIM

The ornamental design for a game wheel, substantially as shown and described.

DESCRIPTION

FIG. 1 is a front perspective view of a game wheel showing our new design;

FIG. 2 is a back elevational view thereof; and

FIG. 3 is a side elevational view thereof, with all side elevational views being the same in appearance in that the design is circular and totally symmetrical around its entire circumference.

FIG. 1

FIG. 2

FIG. 3
